UNITED STATES PATENT OFFICE.

LARRY L. COMEAU, OF BRADFORD, MASSACHUSETTS.

SHOE AND METHOD OF MANUFACTURE.

Application filed April 23, 1926. Serial No. 104,133.

The invention relates primarily to improvements in ladies' shoes of a type which will possess the flexibility, comfort and general appearance of turned shoes, but instead of necessitating the use of expensive and complicated machines commonly employed for manufacturing turned shoes, may have the outer sole and certain other parts stitched on the ordinary Mackay or some similar machine. A shoe of this general type is disclosed in my U. S. Patent No. 1,537,409 of May 12th, 1925, but it is the object of the present invention to improve upon the construction and method disclosed in that patent, in such a manner as to provide a shoe which will have greater rigidity at its shank and heel portions, yet will be flexible to a high degree at its front portion.

With the foregoing in view, the invention resides in the novel subject matter herein-after described and claimed, the descriptive matter being supplemented by the accompanying drawing.

Figures 1, 2 and 3 are perspective views showing different steps in the manufacture of the improved shoe.

Figure 4 is a detail transverse section as indicated by line 4—4 of Fig. 3.

In the manufacture of the shoe, I make use of an ordinary wooden last L. Upon the heel and shank portions of this last, I secure a one-piece heel-and-shank-piece 5 whose front end 6 extends substantially to the ball of the last and is skived to a feather edge. In securing this heel-and shank-piece to the last, any desired number of tacks or the like 7 may be used. Prior to securing this piece 5 to the last, a shank reinforce-
ment 8 is preferably secured to it, said reinforcement being formed preferably of a single strip of metal, while said piece 5 is in most instances cut from a good grade of leather.

Upon the front portion of the last L, I temporarily secure a half-inner-sole 9, for instance, by tacks 10, and this half-inner-sole may be formed of any desired material which will be sufficiently flexible to give the desired results. It is preferably much more flexible than the heel-and-shank-piece 5. It will be seen from Fig. 1, that the rear end of the half-inner-sole 9 is disposed in overlapping relation with the front end of the heel-and-shank-piece 5, said ends being preferably so related that in the com-

pleted shoe, the skived front end 6 of said heel-and-shank-piece, overlies the half-inner-sole 9.

After the members 5 and 9 have been applied to the last, an upper 11 having an in-turned lower edge 12 is applied, and this inturned edge 12 may be secured to the members 5 and 9 in any desired manner, preferably by cementing, and I may if desired, wire the instep portions of the inturned edge 12 together, as at W. The tacks or other fastening means 7—10, are now released or removed and a complete outer sole 13 is applied, said sole being cemented or otherwise secured in place so as to prevent accidental displacement.

The operations above described having been completed, the entire assemblage 5—9—11—13, is removed from the last L, and a single row of stitching 14, preferably formed by a Mackay or similar machine, is passed through the outer sole 13, through the inturned edge 12 of the upper 11, and through the heel-and-shank-piece 5, and this stitching may pass either through or around the edge of the half-inner-sole 9. This stitching preferably starts at a point near the breast of the heel, extends forwardly to the toe of the shoe and then continues rearwardly to a point opposite the starting point. The outer sole is of course channeled as at 15, to receive this stitching, and preferably the heel portion of said sole is split as indicated at 16, so that a portion of it may be turned downwardly as indicated by the dotted lines 17, for finishing the breast of the usual wooden or other preferred type of heel, the latter being secured in place, in any desired manner.

It will of course be understood that if wished, a suitable filler (not shown) may occupy the space between the outer sole and the members 5 and 9, which space is bounded by the inturned edge 12 of the upper 11. It will also be understood that a sock lining (not shown) may be cemented over the entire inner side of the sole if desired.

By the improved method, a shoe is produced whose heel and shank portions are relatively stiff, due to the combined thickness of the outer sole 13 and the heel-and-shank piece 5, whereas the front portion of the sole will be very flexible and hence will be unusually comfortable and desirable.

I have found that excellent results are obtainable from the method steps and the

structural details herein disclosed and they are therefore preferably followed. However, within the scope of the invention as claimed, variations may be made.

5. I claim:—

1. In a process of shoe manufacture, the steps of applying a heel-and-shank-piece to the heel and shank portion of a last, applying a half-inner-sole to the forepart of the 10 last, disposing the rear end of said half-inner-sole in overlapping relation with the front end of said heel-and-shank-piece, applying an upper having an inturned edge to the last and engaging said edge with said 15 heel-and-shank-piece and said half-inner-sole, applying an outer sole and securing it against accidental displacement, removing the assembled parts from the last, and stitching at one operation through the outer sole, 20 through the inturned edge of the upper, through the heel-and-shank-piece and through the half-inner-sole.

2. A shoe comprising an outer sole, an upper having an inturned edge resting on 25 said sole, a half-inner-sole covering the front portion of the outer sole and resting on said inturned edge of the upper, a heel-and-shank-piece covering the heel and shank portion of said outer sole with its front end in 30 lapping relation with the rear end of said half-inner-sole, said heel-and-shank-piece resting on said inturned edge of the upper, and stitching passing through said outer sole, said inturned edge of the upper, and 35 said heel-and-shank-piece.

3. In a process of shoe manufacture, the steps of applying a heel-and-shank-piece to the heel and shank portion of a last, applying a half-inner-sole to the forepart of the 40 last, disposing the rear end of said half-

inner-sole in overlapping relation with the front end of said heel-and-shank-piece, applying an upper having an inturned edge to the last and engaging said edge with said heel-and-shank-piece and said half-inner- 45 sole, applying an outer sole and securing it against accidental displacement, removing the assembled parts from the last, and stitching at one operation through the outer sole, 50 through the inturned edge of the upper, and through the heel and shank piece.

4. A shoe comprising an outer sole, an upper having an inturned edge resting on said sole, a half-inner-sole covering the front portion of the outer sole and resting on said 55 inturned edge of the upper with its edges approximately flush with those of the outer sole, a heel-and-shank-piece covering the heel and shank portion of said outer sole with its front end in lapping relation with the rear end of said half-inner-sole; said heel-and-shank piece resting on said inturned edge of the upper, and stitching passing through said outer sole, said inturned edge of the upper, and said heel-and-shank-piece. 60

5. A shoe comprising an outer sole, an upper having an inturned edge resting on said sole, a half-inner-sole covering the front portion of the outer sole and resting on said 65 inturned edge of the upper, a heel and shank piece extending rearwardly from said half-inner-sole and covering the heel and shank portion of said outer sole, said heel-and-shank-piece resting on said inturned edge of the upper, and stitching passing through 70 said outer sole, said inturned edge of the upper and said heel-and-shank-piece. 75

In testimony whereof I have hereunto affixed my signature.

LARRY L. COMEAU. [L. S.]
